PACKING APPARATUS

George A. Krause, Caldwell, and August Grunewald, Hoboken, N. J., assignors to Colgate-Palmolive-Peet Company, Jersey City, N. J., a corporation of Delaware

Application April 12, 1946, Serial No. 661,840

4 Claims. (Cl. 226—129)

1

The present invention relates to packing apparatus adapted for loading packages into a shipping case or container.

Packages of various commodities such as powdered soaps, prepared cereals and the like, are customarily packed for transportation in predetermined numbers in a shipping case or a container which may be made of corrugated paper, wood or other suitable material. The packages containing the commodity are usually filled and closed on automatic machinery and transported from the filling and closing machine to the packaging station by means of a conveyor. The present invention relates to apparatus adapted to facilitate the removal of packages from such a conveyor and the loading of shipping cases with the desired number of the packages.

Among the objects of the invention are to provide an apparatus for loading shipping cases which is easy to operate, simple in construction, and reliable in its operation; and to provide such an apparatus requiring a minimum of manual labor and effort.

Other objects and advantages of the invention will be apparent from the following detailed description of an illustrative embodiment taken in conjunction with the drawing in which:

Fig. 1 represents a front elevation, partly in section, of the packing apparatus;

Fig. 2 is a top plan view thereof;

Fig. 3 is a section in elevation along the line 3—3 of Fig. 1 looking to the left as indicated by the arrows; and

Fig. 4 is a detail plan view, partly in section, of the mechanism for tilting the trays.

Generally speaking, the apparatus of the present invention is a device for gravity loading shipping cases with a plurality of packages. It comprises means for supporting a group of packages, means for holding a shipping case open at the top directly under the group of packages, and means for removing the support whereby the packages fall by gravity as a group into the shipping case.

Referring now more particularly to the drawing, reference numeral 1 represents a table supported at the rear by legs 3 and provided with a rectangular opening 5 which corresponds substantially to the internal dimensions of the cross section of the shipping case to be loaded. An

2

endless conveyor belt 7 is mounted at one end on a pulley 9 journaled in bearings on the under side of table 1 and at the other end on a similar but driven pulley (not shown). The conveyor belt 7 is adapted to bring packages from a filling and closing machine to the loading table. Between the end of the conveyor belt and the opening 5 is a frictionless run 11 comprising a plurality of rollers 13 journaled in the table 1 over which the packages may be moved with very little effort.

Two trays 15 having a flange 17 at each end thereof, are pivotally mounted in the opening 5 preferably somewhat below the level of the top 15 of the table 1. A convenient way of mounting the trays is shown in Fig. 4 which comprises a rod 19 secured to one edge of the tray and extending beyond the ends thereof through openings in support members 21 which form bearings 20 for the ends of the rods. The support members 21 are secured to the under surface of table 1. It will be seen in the drawings that the trays are pivoted for movement about an axis adjacent to opposite edges of the opening 5. The trays are normally held in substantially horizontal position as illustrated in Figs. 1, 2 and 4 and are capable of swinging downwardly through an angle of about 90° to the position shown in Fig. 3.

Means are provided for moving the trays in unison comprising a bevel gear 23 securely fastened on the rod 19 of the back tray 15, a bevel gear 25 fixedly mounted on a short shaft 27 mounted in bearings 28 secured to the table 1, and a second bevel gear 29 secured to the other end of the shaft 27 which meshes with a further bevel gear 31 fixedly mounted on rod 19 of the front tray 15.

A crank arm 33 is fixedly mounted on rod 19 of the back tray 15. A connecting rod 35 is pivoted at one end to crank arm 33 and at the other end to a treadle 37 which is pivoted to a bracket 39 on the framework of the machine by means of a pin 41 extending through the treadle 37. A bracket 43 mounted on the framework holds one end of a tension spring 45, the other end of which engages a collar 47 which is adjustably mounted on the connecting rod 35 as shown in Fig. 3.

A guide member 49 in the form of an L-shaped

bracket is provided at each edge of the opening 5 adjacent to the edges where the trays are mounted. The one at the right end in Figs. 1 and 4 is secured directly to the table 1 while the one at the left is secured to a bridge member 58 spanning the opening in the table provided for the rollers 18.

The means for supporting a shipping case under the opening 5 comprises a frictionless run 51 having a plurality of rollers 53 mounted in angle irons 55 which are suitably fastened to legs 3. The legs 3 have short posts 57 extending above the angle irons 55. Pairs of guide rods 59 are secured to the legs 3 and posts 57 as shown in Figs. 1 and 3 to assist in positioning a shipping case below opening 5.

The apparatus is adapted for operation by a single human operator who stands on the floor in front of the apparatus as illustrated in Figs. 1 and 2 so that the left foot is near the treadle 37. The conveyor belt 7 operates continuously to deliver the packages from the filling and closing machine onto the table 1 for loading into shipping cases. At the start of the operation, the operator places a shipping case on the frictionless run 51 between the guide bars 59 and directly below the opening 5. A preferred type of shipping case is shown in Fig. 3 by reference character 61. It is made of corrugated paper and comprises four closing flaps at each end. The flaps at the bottom of the shipping case may be closed by the operator at the time it is placed on the frictionless run or they may be closed at any time prior thereto. The flaps at the top of the shipping case stand substantially upright and in moving the case under the opening 5 the flap on the leading side is bent down by the operator so as to clear the guides 49. As soon as the operator releases this flap it swings back to upright position against the outside of the guides 49 under the frictionless run 51, as shown in Figs. 1 and 3. It will be noted that there are no obstructions to interfere with the free movement of the operator's arms during the positioning of the shipping case.

During the time the operator is positioning the shipping case the conveyor brings packages to the table and deposits them on the run 51. The slight pressure of packages arriving at the end of the conveyor suffices to push previously arrived packages along this run, and, depending upon the time taken by the operator to position the shipping case, some 2 to 4 or 5 packages will be on the run. The operator, reaching to the left, groups the proper number between his hands as they are traveling to the right and slides them onto the back tray 15, as shown in Figs. 1 and 2. In this instance six such packages are grouped face to face. A similar group is placed on the front tray 15 in the same manner.

The operator then steps on treadle 37 thereby swinging trays 15 downwardly to the position shown in Fig. 3. This action removes the support for the packages which fall as a group into the shipping case. The trays themselves serve as guides for the edges of the cartons while brackets 49 guide the faces. The shipping case shown in Fig. 3 holds two layers of packages. As soon as the first layer has dropped into the bottom of the case the operator releases the treadle permitting the spring 45 to return the trays to their horizontal position, locates a second group of 12 packages and drops them into the shipping case in the same manner. The filled case is then pushed on to the left along the frictionless run 51 as shown

in Fig. 1, e. g., to a conveyor to transport it to a sealing machine. Another shipping case is then moved into position. Packages which arrived at the table while the operator is removing the filled case and pushing a case to be filled ride along the frictionless run 51 in easy reach of the operator to group and place on the back tray.

The operation of the apparatus requires little effort on the part of the operator. The packages do not need to be lifted but can merely be slid along on the frictionless run 51 to the trays 15. The end flanges 17 on trays serve to locate the group endwise and the edge of the opening 5 serves to locate them crosswise. The spring 45 is of such size and is so adjusted as to keep the trays in substantially horizontal position when loaded but to require little effort to tilt the trays to the dumping position.

Although the present invention has been described and illustrated in connection with a single illustrative embodiment, those skilled in the art will readily recognize that variations and modifications may be resorted to without deviating from the principle of the machine. Thus, for example, if the shipping case were designed to contain a single tier of packages instead of a double tier as shown, a single tray in the opening 5 could be provided. Similarly the bevel gear device for effecting unison of movement in the two trays could be replaced by a linkage mechanism or other equivalent device. The invention also contemplates the use of other types of devices for moving the trays about their axes, for example, a solenoid could be substituted for the treadle 37 to be operated by a push button, or the like. Those and other modifications and variations are contemplated within the scope of the appended claims.

We claim:

1. In an apparatus for packing a shipping case, means for directing a group of packages into an open end of a shipping case comprising two oppositely located fixed vertical guides and two oppositely located hinged plates, said hinged plates being adapted in horizontal position to serve as a support for said group of packages and in vertical position to serve as guides therefor, spring means for holding said plates in horizontal position against the weight of packages thereon, and means under control of the operator for moving said plates from horizontal to vertical position.

2. Apparatus for packing a shipping case comprising a table having an opening, means under said table for holding a shipping case with an open upper end aligned with said opening, means comprising a tray pivoted adjacent one edge of said opening providing a removable support for a plurality of packages, spring means normally holding said tray in horizontal position, and means including a foot treadle for swinging said tray downwardly about its pivot to vertical position.

3. Apparatus comprising in combination a table having a rectangular opening, a conveyor belt adapted to deliver packages to said table, a fixed guide extending downwardly from each of two opposite edges of said opening, a plate pivoted for movement about an axis adjacent to each of the other two edges of said opening, means linking said plates for movement in unison, spring means for holding said plates in horizontal position, means under control of the operator for moving said plates from horizontal to vertical position, and means for holding a shipping case

under said table with its open end aligned with said opening.

4. A packing apparatus comprising a table having an opening, a pair of plates hinged to said table on opposite sides of said opening and somewhat below the level of the table, each of said plates covering somewhat less than half of the opening and being spring held in horizontal position, means linking said plates for movement in unison, means at one side of said table under control of the operator for moving said plates downwardly from horizontal to vertical position, means at the other side of said table constituting its sole support, and means for holding a

shipping case under said table with its open end aligned with said opening.

GEORGE A. KRAUSE.
